UNITED STATES PATENT OFFICE.

ALDEN L. PUTNAM, OF DETROIT, MICHIGAN, ASSIGNOR TO WHITEHEAD & KALES COMPANY, OF RIVER ROUGE, MICHIGAN, A CORPORATION OF MICHIGAN.

DESIGN FOR A VEHICLE WHEEL.

Application filed March 3, 1926. Serial No. 16,754. Term of patent 14 years.

To all whom it may concern:

Be it known that I, ALDEN L. PUTNAM, a citizen of the United States, residing at Detroit, in the county of Wayne and State of Michigan, have invented a new, original, and ornamental Design for a Vehicle Wheel, of which the following is a specification, reference being had to the accompanying drawing, forming part thereof.

Figure 1 is a side elevation of a wheel embodying my invention;

Figure 2 is a perspective view thereof; Figure 3 is a cross sectional view taken on the line 3—3 of Figure 1; and

Figure 4 is a cross sectional view taken on the line 4—4 of Figure 1.

I claim:

The ornamental design for a vehicle wheel, substantially as shown.

ALDEN L. PUTNAM.
